UNITED STATES PATENT OFFICE.

EDMUND A. SCHADE, OF NEW BRITAIN, CONNECTICUT, ASSIGNOR TO THE STANLEY RULE AND LEVEL COMPANY, OF NEW BRITAIN, CONNECTICUT, A CORPORATION OF CONNECTICUT.

LEVELING-STAND AND BASE.

1,151,549.

Specification of Letters Patent. Patented Aug. 24, 1915.

Application filed November 7, 1914. Serial No. 870,827.

To all whom it may concern:

Be it known that I, EDMUND A. SCHADE, a citizen of the United States, residing at the city of New Britain, county of Hartford, State of Connecticut, have invented certain new and useful Improvements in Leveling-Stands and Bases, of which the following is a full, clear, and exact description.

10 My invention relates to an improved and simplified form of transit stand, the object being to provide an exceedingly simple and inexpensive device, available to many who neither have the need for, nor the means necessary for the purchase of, the usual high-grade instrument.

15 In the drawings, Figure 1 is a perspective view of my invention. Fig. 2 is a plan view thereof. Fig. 3 is a section on the plane of the line 3—3.

20 1 represents a suitable platform provided with appropriate means for mounting the usual spirit level thereon. In this instance the stand is provided with rigid abutments 2, 2 at one side and the movable clamping abutment 3 at the opposite side, by which the level may be held. The stand 1 is mounted upon the upper section of what I may term a turn-table 4 and is preferably 25 integral therewith. 5 represents the lower section of the turn-table, which supports the upper section 4, the contact faces of these table sections being uniformly flat so that accurate adjustment is assured. The 30 lower section 5 has projecting therefrom three legs 6, 7 and 8, which in turn are arranged to coat with three radial arms 9, 10 and 11, respectively. These arms 9, 10 and 11 radiate from the head-piece 12, 35 which is cupped on its lower side to provide a socket centrally thereof designed to receive a supporting member such as a post 14 which may be any convenient post, rod or stake capable of being supported substantially vertically in the ground and of a size 40 to enter within the cup or socket of the head.

45 15, 15 are clamping screws for clamping the head 12 upon the post 14.

50 16, 17 and 18 are adjustment screws operating between the legs 6, 7 and 8 and the supporting arms 9, 10 and 11. In this instance the said adjusting screws pass through threaded sockets or bores in the lower ends of the legs 6, 7 and 8 and make

55 engagement with the arms 9, 10 and 11. The lower turn-table section 5 is coupled with the head 12 by a screw 19 located near but slightly to one side of the center line of the parts. One end of the screw 19 rotates freely in one of the connected members—in 60 this instance the turn-table section 5—and is threaded into the other member—in this instance the head 12. The upper turn-table section 4 may be clamped to the lower turn-table section 5 by a combined central pivot 65 and clamping screw 20, the said clamping screw having a head or thumb-piece, arranged below the turn-table 5, the threaded end of the screw taking into the threaded opening in the center of the upper turn-table section 4.

70 22 is a screw passing centrally down through the upper part of the head 12, the function being merely to engage the upper end of the post 14 and steady it in the event 75 that the post is smaller than the socket formed at the underside of the head.

75 In operation, the instrument is first secured upon the upper end of the post 14 or other similar support, which may be set 80 firmly in the ground and preferably in approximately a vertical position. The upper section 4 of the turn-table may then be turned into the position shown in Fig. 2, wherein the level 23 supported thereon will 85 be located in a line substantially parallel to a line intersecting the centers of the screws 17 and 18. The turn-table section 4 is then locked in that position by the screw 20. The screws 17, 18 are then adjusted until the 90 level instrument 23 stands in a perfectly level position. The lock-screw 20 is then released and the level is turned at right angles to the position shown in Fig. 2, whereupon the supporting turn-table section 4 is 95 again locked in place by the screw 20. The adjusting screw 16 may then be turned to bring the leveling instrument to the level position when pointed in this second direction. The adjusting screw 20 may then be 100 released again and the level may be turned at all different angles to determine whether it is correctly set, any slight deviation being then readily detected and overcome by the very slight rotation and adjustment of the 105 proper one of the screws 16, 17 or 18. When it is determined that the instrument is accurately positioned, the two parts of the

stand,—that is to say the lower section 5 of the turn-table and the head 12,—may be locked together by turning down the screw 19.

As shown in Fig. 1, the level is preferably provided with sighting devices, one sight being indicated at 24, which sighting devices are well-known and for which I make no claim of novelty herein, my invention being based upon the novel form of combined adjustable support and stand whereby an ordinary spirit level may be effectively used as a transit instrument.

What I claim is:

In a transit stand, a turntable comprising upper and lower relatively rotatable members, means on said upper member for removably clamping a level, a centrally located combined pivot and clamping screw pivoting said members together and for

securing said members in rotatably adjusted relation, said clamping screw being provided with an operating portion centrally located below the lower turntable member, a supporting head provided with a socket to receive the end of a supporting post, leveling screws between the head and lower turntable member and a single coupling screw engaged between the supporting head and lower turntable section adjacent the center thereof, releasable to allow the turntable to be freely adjusted by the leveling screws and adapted to be set to clamp the turntable in its leveled position on the supporting head.

EDMUND A. SCHADE.
